UNITED STATES PATENT OFFICE.

LOUIS A. STINSON, OF CHICAGO, ILLINOIS.

BUILDING.

SPECIFICATION forming part of Letters Patent No. 650,662, dated May 29, 1900.

Application filed October 14, 1899. Serial No. 733,573. (No model.)

To all whom it may concern:

Be it known that I, LOUIS A. STINSON, a citizen of Canada, residing at Chicago, in the county of Cook and State of Illinois, have invented certain new and useful Improvements 5 in Buildings, of which the following is a specification.

The present invention relates more particularly to the class of buildings that are used 10 for the storage of grain and the like; but many, if not all, of its several novel features may be embodied in buildings for other purposes. My chief aim having been to provide a building particularly adapted for the storage of 15 grain, I have selected this embodiment of it for the purposes of this application and have shown it as embodied in a bin structure comprising a number of vertical compartments. It will, however, be understood that the invention 20 is in no wise limited to the number of compartments that the building may contain, excepting in so far as the invention or some features of it can be embodied only in a structure having a plurality of such compartments. In other words, some features 25 of the invention are applicable to a structure having only the outside walls and without any inside walls or partitions whatever, while other features of the invention are applicable 30 to and can have their embodiment in only such structures as have inside walls dividing them into a plurality of compartments.

The object of the invention is to provide a building of low cost which shall nevertheless 35 possess the requisite strength and stability and which shall at the same time be of simple construction. To this end, a suitable foundation being provided, I construct the building of horizontal sills or sleepers, a horizontal course of flanged beams (preferably 40 channel-irons) resting upon the sills and having their flanges presented upward, a horizontal course of thin sheathing, preferably corrugated sheet iron or steel, resting at its 45 lower edge in the channel formed by the upwardly-presented flanges aforesaid, a horizontal course of flanged beams (preferably channel-irons) resting upon the upper edge of the sheathing, so that said upper edge of 50 the sheathing occupies the channel formed by the downwardly-presented flanges, and means for securing the several courses to

gether, said courses being repeated in the order enumerated until the desired height is reached.

55

The invention consists in the features of novelty herein described.

In order that the invention may be fully understood, I will describe it with reference to the accompanying drawings, which are 60 made a part hereof, and in which—

Figure 1 is a sectional elevation of a structure embodying the invention, the section being taken on the line 1 1, Fig. 2, and the parts being viewed in the direction of the arrow. Fig. 2 is a horizontal section thereof on the line 2 2, Fig. 1, some of the features shown in Fig. 1 being, however, omitted from Fig. 2. Fig. 3 is a plan view of one of the horizontal courses of flanged beams, showing 65 their arrangement when channel-irons are used in a structure having sixteen rectangular compartments. Fig. 4 is a plan view of another course of channel-irons in the same structure, the difference between the two figures being that Fig. 3 shows a course having the flanges presented upward, while Fig. 4 shows a course having the flanges presented 70 downward. In the completed structure the course shown in Fig. 3 rests immediately 75 upon the course shown in Fig. 4. Fig. 5 is an enlarged sectional elevation on the line 5 5, Fig. 6, looking in the direction of the arrow. Fig. 6 is a plan view on the same scale as Fig. 5 of a portion of a structure embodying the invention. Fig. 7 is a sectional elevation showing the manner of connecting the ends of the tie-rods with the flanged beams. Fig. 8 is a section on the line 8 8, Fig. 6, looking in the direction of the arrow. 80 Fig. 9 is a sectional elevation of a fragment of a structure embodying some features of the invention and showing the use of I-beams instead of channel-irons, as in the preceding figures. Fig. 10 is a plan view thereof with 85 portions broken away, showing the arrangement of the I-beams.

A are a number of heavy beams suitably supported and arranged to form sills, one sill being provided for each wall of the structure. 90

B B', B'', &c., are channel-irons arranged in a horizontal course (all in the same plane) upon the sills A and having their flanges presented upward, said channel-irons being suit-

ably secured to the sills, so as to prevent their displacement.

C C' C², &c., are sheets of corrugated metal, preferably steel, arranged in a horizontal course and resting at their lower edges in the channels of the channel-irons B B', &c., the meeting ends of said sheets being permanently secured together by bolts or rivets c, the preferred manner of bringing said ends together being more clearly shown in Fig. 6—that is to say, the final corrugations of two adjoining sheets are arranged concentrically and the meeting edges of all the sheets are secured together by bolts or rivets.

15 D D' D², &c., are channel-irons arranged in a horizontal course resting upon the upper edges of the corrugated sheets C C', &c., and having their flanges presented downward, so that the upper edges of the sheets are received

20 in the channels of the channel-irons D D', &c. The manner of disposing this horizontal course of channel-irons D D', &c., in a structure having sixteen compartments (only two of which are fully shown in Figs. 1 and 2) is 25 shown in Fig. 4. They are all disposed in the same horizontal plane, but with the end or ends of each abutting against the side of another or others. Wherever it is possible, regard being had for their relations to the superposed horizontal course, which is shown in Fig. 3 and will presently be described, I use pieces of channel-iron long enough to span two compartments of the structure, and I stagger them in both directions; but where it is 30 not possible to use these long pieces pieces of practically one-half their length and spanning only one compartment of the structure are used. For example, the long sections D', D³, D⁴, D⁵, D⁶, and D⁷, running in one direction, 35 are staggered, and the long sections D⁸, D⁹, D¹⁰, and D¹¹, running in the other direction, are staggered; but the two remaining long sections D¹² and D¹³ cannot be staggered, for the reason that the sections of this course of 40 channel-irons shall break joints with the sections of the course shown in Fig. 3. The sections D, D², and D¹⁴ and the corresponding sections at the other corners of the course are of necessity short, and while this is unavoidable it is not objectionable, for the reason 45 that the correspondingly-located sections of the superposed course are long and break joints at the ends of these short sections.

E E' E², &c., are channel-irons which have 50 their flanges presented upward and which are arranged in a horizontal course upon the corresponding channel-irons of the course shown in Fig. 4. As before stated, all the channel-irons of this course (see Fig. 3) break joints 55 with the channel-irons of the course last above described. For example, the section E overlaps the end of the section D¹⁴, completely covers the section D, overlaps the end of the section D', and covers practically one-half of the section D¹², so that all the joints between D¹⁴, D, D', and D¹² are broken by the section E. It is not necessary to thus follow out in

detail the disposition of the several sections of this horizontal course of channel-irons, as it will be apparent from an inspection of Figs. 70 3 and 4 that the break-joint arrangement is adhered to throughout, and the double-length sections are used wherever this can be done without bringing two joints together.

F F' F², &c., are sheets of corrugated metal, 75 preferably steel, arranged in a horizontal course resting in the channels of the irons E E' E², &c., and forming the sheathing or walls of the structure, and G G' G², &c., are channel-irons arranged in a horizontal course 80 resting upon the corrugated sheets F F' F², &c., and having their flanges presented downward in the manner already described with reference to the channel-irons D D', &c., and the corrugated sheets C C', &c. In order to 85 build up the structure to the desired height, the arrangement already described is simply repeated.

The channel-irons D D' D², &c., are secured to the channel-irons E E' E², &c., by 90 means of bolts and nuts or rivets, as shown at d, one or more of such bolts or rivets being passed through the web of each abutting end of each channel-iron of each horizontal course and through the web of the channel-iron of 95 the next course which breaks the joint. The holes for these securing devices are represented by the large circles in Fig. 4, and the exact disposition of the bolts at the intersection of, say, the channel-irons E E' E² E³ and 100 those immediately below them being shown on a larger scale in Fig. 6. From Figs. 5, 6, and 8 it will be seen that the long sections D' and E², with their flat faces together, cross each other at the middle. The extremities 105 of the sections D² and D⁸ abut against the sides of the section D', and the extremities of the sections E' and E³ abut against the sides of the section E², the abutting extremities of the sections D², D⁸, E', and E³ being 110 secured to the webs of the sections D' and E² by the bolts d.

H represents tie-rods passed through the webs of the channel-irons D D' D², &c., E E' E², &c., and I represents similar tie-rods passed 115 through the webs of the channel-irons D D' D², &c., E E' E², &c., G G' G², &c., and the next horizontal course resting upon them for the purpose of holding the structure together vertically. Any desired number of these tie-rods may be used, the perforations for them 120 being represented by the small circles in Figs. 3 and 4.

For the purpose of bracing the structure horizontally tie-rods J may be arranged across 125 the several compartments of the structure, the ends of said tie-rods being connected with the flanged beams by means of hooks K, as shown in Fig. 7. Each of these hooks consists of a plate bent to form the three sides 130 of what is substantially a rectangle, one side of each being perforated for the passage of the tie-rod, which is held in place in the perforation and drawn tight by means of a nut

L. Any desired number of these tie-rods may be used, and they may be disposed as shown in the drawings or in any other preferred manner.

5 It will be observed that at the intersections of the several channel-irons the flanges are left intact, and in order to accommodate them the corrugated sheets are notched, as shown more clearly in Fig. 8.

10 In order to shed water on the outside of the structure and to prevent the lodgment of grain on the inside of the structure, the spaces between the upwardly-presented flanges of the channel-irons and the opposite faces of

15 the corrugated sheets are filled with cement or other substance, as shown at M, the upper face of this filling being sloped, as shown more clearly in Fig. 5.

It will be observed that a characteristic of 20 the structure thus far described is that there are no upright beams or girders, the office of such beams or girders being filled by the corrugated sheets, which have their vertical edges directly united.

25 I have shown in Figs. 9 and 10 a structure in which I-beams are used instead of channel-irons. When I-beams are used, it is possible to use greater lengths, or at any rate lengths passing a greater number of intersections, than where channel-irons are used.

30 It is desirable, however, that in this I-beam structure the joints shall occur directly at the intersections, where for the purpose of supporting the webs of the beams blocks N

35 are arranged, said blocks being secured in place by the bolts which secure together the intersecting beams. Excepting to the extent due to the difference between the form of an I-beam and the form of a channel-iron the

40 structure shown in Figs. 9 and 10 does not differ from that shown in the preceding figures.

What I claim as new, and desire to secure by Letters Patent, is—

45 1. A building having plural horizontal courses of sheathing, flanged beams arranged between each course of sheathing and the next and supported solely by the course of sheathing immediately below them, said

50 beams being overlapped at their intersections, and means for securing together the overlapped portions of the beams, thereby forming of them a connected horizontal framework, substantially as described.

55 2. A building having plural horizontal courses of sheathing made up of vertically-corrugated plates, means for directly securing together the meeting vertical edges of the sheathing-plates, flanged beams arranged be-

60 tween each course of sheathing and the next, the horizontal edges of the sheathing-plates being confined between the upturned and downturned flanges of the beams, said beams being overlapped at their intersections, and

65 means for securing together the overlapped portions of the beams, thereby forming of

them a connected horizontal framework, substantially as described.

3. A building having plural horizontal courses of sheathing made up of vertically-corrugated plates, means for securing together the vertical edges of the plates, plural horizontal courses of flanged beams arranged above and below each course of sheathing-plates, so that the horizontal edges of the 75 sheathing-plates are confined between the flanges of the beams, and tie-rods connecting each course of flanged beams with a course above it and a course below it, substantially as described.

4. A building having plural horizontal courses of sheathing made up of vertically-corrugated plates, means for securing together the vertical edges of the plates, plural horizontal courses of flanged beams arranged 85 above and below each course of sheathing-plates, so that the horizontal edges of the sheathing-plates are confined between the flanges of the beams, the beams being overlapped at their intersections, and means for 90 securing together the overlapped portions of the beams, thereby forming of them a connected horizontal framework, substantially as described.

5. A building made up of a horizontal 95 course of beams having flanges presented upward, a horizontal course of sheathing made up of vertically-corrugated plates having their lower edges confined between the flanges of said beams, means for securing together 100 the vertical edges of the sheathing-plates, a superposed horizontal course of sheathing-plates similar to the first course, means for securing together the vertical edges of said sheathing-plates, flanged beams interposed 105 between the two courses of sheathing-plates and having flanges projecting downward and confining the upper edges of the lower course of sheathing-plates, and flanges projecting upward and confining the lower edges of the 110 upper course of sheathing-plates, said beams being overlapped at their intersections, means for securing together the overlapped portions of the beams, a course of flanged beams resting upon and supported by the upper course of 115 sheathing-plates and having flanges presented downward between which the upper edges of the upper course of sheathing-plates are confined, and means for connecting together the several courses of beams so as to prevent 120 their separation, substantially as described.

6. A building having a horizontal course of sheathing made up of vertically-corrugated plates, the final corrugations in the vertical edges of adjacent plates being brought together, means for securing said final corrugations together, a horizontal course of flanged beams located below said course of sheathing-plates and having flanges presented upward and confining the lower edges of the sheathing- 125 plates, a horizontal course of flanged beams located above said course of sheathing-plates 130

and having flanges presented downward and confining the upper edges of said sheathing-plates, one or more repetitions in vertical courses of the parts above described, and tie-
5 rods for connecting the several courses of flanged beams, substantially as described.

7. A building made up of alternating courses of flanged beams and sheathing-plates, each course supporting those above it,
10 the top and bottom edges of the plates being confined between the flanges of the beams, and a filling occupying the space between the flanges of the beams and plates, the top surface of said filling being sloped toward the
15 flanges, substantially as described.

8. A building having plural courses of sheathing-plates and channel-irons arranged in two horizontal courses between each course of sheathing-plates and the next, the chan-

nel-irons of one course having their flanges 20 presented downward and the channel-irons of the other course having their flanges presented upward, the channel-irons of one course being arranged to break joints with the channel-irons of the other course, sub- 25 substantially as set forth.

9. In a building, a horizontal course of channel-irons arranged in intersecting rows, the sections of channel-irons in each row being staggered, and a second horizontal course 30 of channel-irons similarly arranged and breaking joints with the channel-irons of the first course, substantially as set forth.
